UNITED STATES PATENT OFFICE

2,578,412

SPRAY GUN FOR COMMUNICATED MATERIAL
AND ADHESIVE

Emery J. Fisher, Chicago, Ill.

Application January 10, 1950, Serial No. 137,873

2 Claims. (Cl. 91—45)

1

My present invention relates to guns for spraying comminuted materials and simultaneously spraying a liquid onto the blast of comminuted material as it leaves the gun. More specifically, the invention relates to certain innovations and improvements in the type of spray gun disclosed in Patent No. 2,433,463, issued December 30, 1947, to A. J. Lampe.

This type of spray gun is particularly useful for spraying comminuted insulation materials onto walls or other surfaces. In order for the comminuted material, which may be for heat or sound insulation, to adhere to the wall surface and form a continuous blanket, it is necessary to at least partially coat the individual particles or pieces with a suitable binder or adhesive. This method or technique of applying and building up mats of insulation on selected surfaces is disclosed in Patents Nos. 1,718,507, 1,888,841, 2,179,679 to Wenzel et al., No. 1,837,422 to Fix, and No. 1,978,125 to Bennett.

The spray gun disclosed in detail in Lampe Patent No. 2,433,463 has proven, through extended experience, to be a satisfactory device for the purpose intended. Even so, by the present invention I am able to transform the Lampe type spray gun into one which functions even more satisfactorily in several respects.

The object of the invention is the provision of a spray gun of the type shown and described in the Lampe Patent No. 2,433,463, which in comparison with the Lampe type structure is: (1) easier and cheaper to build; (2) has increased efficiency and capacity for the same size unit; (3) provides a more trouble-free construction; and (4) is easier to handle and more convenient to take down and clean.

Certain other objects of the invention will, in part, be obvious and will, in part, appear herein-after.

For a more complete understanding of the nature and scope of my invention, reference may now be had to the following detailed description thereof taken in connection with the accompanying drawings, wherein:

Fig. 1 is a top plan view of a spray gun in the horizontal position forming one embodiment of the present invention;

Fig. 2 is a front end elevational view of the spray gun shown in Fig. 1;

Fig. 3 is a sectional view taken on line 3—3 of Fig. 2;

Fig. 4 is a longitudinal sectional view taken on line 4—4 of Fig. 2;

Fig. 5 is an enlarged detail sectional view taken on line 5—5 of Fig. 2;

2

Fig. 6 is an enlarged elevational view of the base section of the annular spray head shown with the cover section removed therefrom; and

Fig. 7 is an enlarged elevational view on the same scale as Fig. 6 showing the rear side of the spray head cover section with the rubber gasket partially broken away.

Referring now to Fig. 1 of the drawings, the spray gun is indicated generally at 10 and includes a central pipe or conduit 11 through which comminuted insulating material is adapted to be blown under pressure in large volumes, and an annular-shaped liquid spray head 12 fitting over the discharge end of the central pipe 11. The annular spray head 12 is supplied with liquid adhesive under pressure through a small diameter conduit 13, and is supplied with air under pressure through the small diameter conduit 14. The conduits 13 and 14 communicate with inlet 15 and 20 passageways provided in the base section 15 of the spray head 12 as will be described in detail below.

The present invention resides in the construction of the annular shaped liquid spray head 12 with the other portions of the spray gun 10 corresponding to the construction disclosed in the Lampe Patent 2,433,463. The spray head 12 is adapted to be interchangeable with the spray heads previously used on the spray guns of this type.

The spray head 12 has two main parts. One is the annular shaped base section 15 and the other is the annular shaped cover 16 therefor. Each of these sections has a central opening which permits the respective sections to fit over the discharge end of the central tube 11. The spray head 12 is held in position on the discharge end of the central pipe 11 by the two conduits 13 and 14 running along opposite sides thereof. These conduits extend through openings provided therefor in ears 17 and 18 integrally projecting on opposite sides of a ring or collar member 20 which fits over the central pipe 11. A set screw 21 locks the ring 20 in place on the pipe 11 and the conduits 13 and 14 are locked in position by set screws 22 and 23 respectively.

The construction of the base section 15 of the spray head 12 is shown in Figs. 1, 3, 4 and 6. The base section 15 has a rear wall 24 (Fig. 4) from the rear of which projects an integral collar portion 25 having diametrically opposed ears 19—19 (Fig. 3).

Three continuous annular walls 26, 27 and 28 (Figs. 3 and 6) project forwardly from the rear wall 24. The annular wall 26 forms the exterior side wall of the section 15. The annular wall

28 forms the inner side wall of the spray section 15 and defines a portion of the length of the opening through the base section 15 for receiving the pipe 11. The annular wall 27 is intermediate between the annular walls 26 and 28 and serves to separate or partition the forward part of the base section 15 into an inner continuous annular chamber 30 and an outer continuous annular chamber 31. It will be noted that the front edges of the annular walls 26, 27 and 28 all lie in the same vertical plane.

As will be more completely described herein-after the inner chamber 30 serves as the distributing or manifold chamber for supplying liquid to the several nozzles mounted in the cover section 16. The outer chamber 31 serves as the distributing passageway or manifold for supplying air to each of these nozzles. Liquid adhesive and air, both under pressure, are admitted to the respective annular chambers 30, 31 from the rear side of the base section 15 through straight openings or ports 32 and 33, respectively (Fig. 3) extending through the ears 19. The passageways 32 and 33 are tapped or threaded for a portion of the distance into the rear of the base section 15 so as to receive the threaded ends of the conduits or pipes 13 and 14. The passageways 32 and 33 are symmetrically located 180° apart and the centers of these passageways are located the same radial distance from the center of the base section 15.

It will be noted from Figs. 3 and 6 that the passageway 32 for the adhesive leads directly into the annular chamber 30. Because of its symmetrical location, the passageway 33 would also lead directly into the chamber 30 but it is baffled or separated therefrom by means of an inwardly protruding bulge or deformity 34 in the partition wall 27 which is shown to advantage in Fig. 6. This bulge 34 serves to place the air inlet passageway 33 into communication with the annular air distributing chamber 31.

The feature of having the adhesive and air passageways 32 and 33 extend directly through the rear wall 24 of the base section 15 without bends or turns, is an important one from several standpoints. From the standpoint of cost of production, it is the most economical and inexpensive design obtainable. For example, base section 15 will normally be a casting and the passageways 32 and 33 may be formed directly in the casting leaving only the tapping or threading operation to be performed. If the base section 15 is formed in other ways than by casting, the formation of the passageways 32 and 33 will still constitute an inexpensive and convenient operation. From the standpoint of operation, the large diameter, straight admission passageways 32 and 33 permit efficient delivery of adhesive and air under pressure. Since there are no turns or restrictions in the passageways 32 and 33, the adhesive and the air are delivered without loss of velocity or pressure such as occurs in passing around a sharp bend or through a constricted passageway. Also, the unrestricted and straight inlet ports 32 and 33 eliminate pulsations due to irregularities in flow.

Referring to Figs. 4 and 6, it will be noted that the annular wall 27 is provided with four integrally formed, diametrically opposed, bosses 35-35. This number could, of course be larger or smaller. Each of these bosses is tapped so as to receive the threaded end of a bolt 36 which, together with the other three bolts 36 serve to securely clamp the cover section 16 on the base

15. The bolts 36 have heads 37 which are circular on the outside and which have hexagonal socket openings 38 (Fig. 2) formed therein for receiving a socket wrench. The cover section 16 is provided with four counterbored recesses 40-40 so that the bolt heads 37 are located below the front surface of the cover section 16.

The inner annular wall of the base section 15 is provided with diametrically opposed bosses or ears 41-41 as shown in Figs. 4 and 6 which are provided with recesses or depressions 42-42 in the top surfaces thereof for receiving the ends of a pair of bolts 43-43 which may be used to forceably separate the cover section 16 from the base section 15. The bolts 43 extend through threaded openings provided therefor in the cover 16, these openings being counterbored as indicated at 44 so as to provide space for the cylindrical bolt heads 45. These bolt heads 45 are provided with hexagonal sockets 49 as indicated in Fig. 2. For convenience, the sockets 49 and the sockets 38 are of the same size so that the one tool may be used for the bolts 36 and 43.

The cover section 16, has in part, been described above. It has a rear portion 46 of enlarged diameter so as to exactly cover or match the open face of the base section 15. The cover section 16 is of generally solid construction except for where it has been tapped to receive the adhesive spray nozzles 47-47 and the bolts 36 and 43. In the rear face of the cover section 16 an annular, V-shaped groove 48 is provided which opposes and has the same width at the base as, the annular air chamber 31 in the base section 15.

Referring to Fig. 5 it will be seen that each of the nozzles 47 fits in a tapped opening provided therefor through the cover section 16, these tapped holes being six in number and being symmetrically located. It will of course be understood that a smaller or larger number of the nozzles may be used. A preferred arrangement of the nozzles 47 is to have each diametrically opposed pair aligned so as to discharge spray streams which converge at a specified distance in front of the gun 10, this distance being different for each of the three pairs of nozzles. For example, very satisfactory operations have been obtained when one pair of the nozzles converge at 24 inches, a second pair converge at 32 inches and the third pair converge at 40 inches, in front of the gun 10. Again, it will be understood that these distances are not critical and other distances may be used as desired.

The nozzles themselves and their particular converging arrangement does not form a feature of the present invention.

In fact, the spray nozzles used in the aforementioned Lampe Patent 2,433,463 can be used in the spray gun 10. Each of the nozzles 47 is provided with an insert member 50 which screws into the central opening through the nozzle from the rear side so as to form an inlet passage for admitting the liquid adhesive into the nozzle chamber 51. Air under pressure is admitted to the chamber 51 through a communicating passage 52 communicating with the V-shaped annular groove 46 at one end and with the nozzle chamber 51 at the other. The air and the adhesive discharge from each of the nozzles 47 through the nozzle opening 52.

It will usually be desirable to employ an annular gasket 53 between the base section and the cover 16. Referring to Fig. 7 it will be noted that the gasket 53 has openings 54-54 for the rear end of the nozzles 47; smaller diameter holes

55—55 for the four clamping bolts 36; two small diameter holes 56—56 for the cover separating bolts 43; and six square or rectangular windows 57—57 overlying the V-shaped annular groove 48 and circumferentially registering with the air passages 52—52.

When the clamping bolts 36—36 are turned down so as to securely draw the cover section 16 onto the base section 15, with the gasket 53 compressed therebetween, the top surfaces of the four bosses 35—35 serve as reinforcing piers to evenly and uniformly support the pressure between the sections 15 and 16 with the top edge of the annular wall 27 bearing a portion of this load. The inwardly protruding bulge or deformity 34 also constitutes a reinforcement for supporting this bearing load. Because of this arrangement an even and tight fit between the cover 16 and the base 15 is assured without any tendency toward warping or twisting, or binding of the clamping bolts 36. This secure and even fit permits the gun 10 to be used under high pressure with respect to the liquid adhesive and atomizing air. The bosses 35—35 also serve to prevent adhesive in the chamber 30 from contacting and fouling the clamping bolts 36.

Heretofore, difficulty has often been encountered in taking apart a spray gun of the type to which gun 10 belongs, for cleaning or adjustment of nozzles, after it has been used. The adhesive sets and tends to secure the parts together so that the cover 16 cannot be easily removed. However, in the gun 10, the separating bolts 43 are used to break the adhesive seal so that the cover 16 may be readily removed. Thus, in removing the cover 16 from the base 15, the four clamping bolts 36 are first unscrewed and then the separating bolts 43—43 are turned in. As soon as the ends of these bolts 43 engage in the bottoms of the recesses 42 a separating force is exerted between the cover 16 and the base 15. By alternately turning first one of the bolts 43 and then another, the cover 16 is forced evenly away from the base 15 so that it may be readily removed by sliding off the forward end of the central pipe 11.

It will be understood that certain changes and modifications may be made in the embodiment of the invention described above and shown in the accompanying drawings, without departing from the spirit and scope of the invention.

Having fully described the invention and a preferred embodiment thereof, what is claimed as new is:

1. An annular shaped liquid adhesive spray head for combination on a gun for blowing comminuted material onto a wall surface and simultaneously spraying a liquid adhesive onto the blast of comminuted material as it is discharged from the gun, said gun having a central pipe through which the comminuted material is blown and over the discharge end of which said spray head fits and from the rear of which spray head conduit connections extend for separately supplying liquid adhesive and air under pressure thereto, said annular shaped spray head comprising, in combination: a flat annular base section; a flat annular interfitting and matching cover section therefor; and clamping bolts for securing said sections together; said base section having inner and outer annular shaped chambers formed therein which open toward the front side thereof, said inner and outer chambers being separated from each other and in part defined by an intermediate annular partition projecting forwardly from the rear wall of said base section, an inner

annular wall projecting forwardly from said rear wall and forming the inner side wall of said inner annular chamber, an outer annular wall projecting forwardly from said rear wall and forming the outer side wall of said outer annular chamber, said rear wall having a pair of circumferentially spaced and diametrically aligned straight adhesive and air admission passageways extending therethrough parallel to the principal axis of said base section, said annular partition having an inwardly protruding bulge therein extending part way into said inner annular chamber, said bulge being in coaxial alignment with one of said inlet passageways whereby that passageway communicates solely with said outer annular chamber, the other of said inlet passageways communicating into said inner annular chamber, said inlet passageways being adapted to be connected with said conduit connections for separately supplying liquid adhesive and air to the respective annular chambers, and a plurality of circumferentially spaced integral bosses protruding from said intermediate annular partition with the faces of said bosses coplanar with the front edge of said annular partition and having holes tapped therein parallel to the principal axis of said base section for receiving said clamping bolts, said cover section comprising an annular member adapted to fit over and mate with said base section so as to close off said inner and outer annular chambers, said annular member having circumferentially spaced nozzle-receiving sockets therein which communicate at their bases with said inner annular chamber, and having individual passageways therein corresponding in number to said sockets and providing communication between said outer annular chamber and each of said sockets intermediate the opposite ends thereof.

2. An annular shaped liquid adhesive spray head for combination on a gun for blowing comminuted material onto a wall surface and simultaneously spraying a liquid adhesive onto the blast of comminuted material as it is discharged from the gun, said gun having a central pipe through which the comminuted material is blown and over the discharge end of which said spray head fits and from the rear of which spray head conduit connections extend for separately supplying liquid adhesive and air under pressure thereto, said annular shaped spray head comprising, in combination: a flat annular base section; a flat annular interfitting and matching cover section therefor; clamping bolts for securing said sections together; and separating bolts for prying said sections apart; said base section having inner and outer annular shaped chambers formed therein which open toward the front side thereof, said inner and outer chambers being separated from each other and in part defined by an intermediate annular partition projecting forwardly from the rear wall of said base section, an inner annular wall projecting forwardly from said rear wall and forming the inner side wall of said inner annular chamber, an outer annular wall projecting forwardly from said rear wall and forming the outer side wall of said outer annular chamber, said rear wall having a pair of circumferentially spaced and diametrically aligned straight adhesive and air admission passageways extending therethrough parallel to the principal axis of said base section, said annular partition having an inwardly protruding bulge therein extending part way into said inner annular chamber, said bulge being in coaxial align-

ment with one of said inlet passageways whereby that passageway communicates solely with said outer annular chamber, the other of said inlet passageways communicating into said inner annular chamber, said inlet passageways being adapted to be connected with said conduit connections for separately supplying liquid adhesive and air to the respective annular chambers, a plurality of circumferentially spaced integral bosses protruding from said intermediate annular partition into said inner annular chamber with the faces of said bosses coplanar with the front edge of said annular partition and having holes tapped therein parallel to the principal axis of said base section for receiving said clamping bolts, and at least one pair of diametrically spaced integral ears protruding from said inner annular wall into said inner annular chamber, said ears having bolt end receiving recesses in the front surfaces thereof for receiving the ends of said separating bolts; said cover section comprising an annular member adapted to fit over

and mate with said base section so as to close off said inner and outer annular chambers, said annular member having circumferentially spaced nozzle-receiving sockets therein which communicate at their bases with said inner annular chamber, and having individual passageways therein corresponding in number to said sockets and providing communication between said outer annular chamber and each of said sockets intermediate the opposite ends thereof.
